UNITED STATES PATENT OFFICE.

JOHN McLUCKIE, OF LONG POINT, ILLINOIS.

PAPER-PUNCH.

1,174,883.

Specification of Letters Patent.

Patented Mar. 7, 1916.

Application filed July 2, 1915. Serial No. 37,728.

To all whom it may concern:

Be it known that I, JOHN McLUCKIE, a citizen of the United States, residing at Long Point, in the county of Livingston and 5 State of Illinois, have invented new and useful Improvements in Paper-Punches, of which the following is a specification.

This invention relates to improvements in paper punches of that particular type having a pair of punch members adapted to simultaneously form a pair of spaced openings in a sheet of paper, to properly prepare the paper to be filed upon a filing device having spaced filing pins.

15 In this class of punching devices, it has been customary to mount the punch pins upon a rigid base plate, between which and a superposed resilient jaw or punch plate the paper is inserted, said resilient jaw or 20 punch plate having openings for the passage of the punch pins, whereby when the movable jaw is operated by means of a cam lever or the like the paper will be punched and the portions of the paper punched out 25 discharged through said openings. Heretofore it has been customary to effect the ejection or discharge of the punched out portions of paper by means of resilient sleeves of rubber inclosing the punch tubes. 30 These sleeves however become inoperative after a comparatively short period, owing either to the disintegration of the rubber or its loss of elasticity.

The object of my invention is to provide 35 a punch of the general character specified, which may be of an all metal construction, and in which a novel construction of ejecting spring is employed in place of the rubber sleeves, by means of which an inexpensive and efficient as well as a highly durable 40 type of punch is produced.

The invention consists of the features of construction, combination and arrangement of parts herein fully described and claimed, 45 reference being had to the accompanying drawing in which:—

Figure 1 is a perspective view of a paper punch embodying my invention, showing in full and dotted lines the normal and working positions of the cam lever. Fig. 2 is a 50 top plan view of the same. Fig. 3 is a vertical transverse section taken on the line of the major axis of the ejecting spring.

Referring to the drawing, 1 designates 55 the punch as a whole, which comprises a

rigid base plate 2 provided with upwardly extending supporting posts 3. Arranged in superposed relation to said base plate is a movable jaw or punch plate 4, made of spring metal, and which normally projects 60 upwardly and forwardly at an angle from the base plate, to provide a space 5 for the insertion of the edge of the paper to be punched and its subsequent removal. The rear edges of the plates are suitably united 65 as by rivets 6, and the plate 4 is provided with openings 7 for the passage of the posts 3, which posts pivotally support an operating lever 8 having cam members 9. This lever is adapted to be moved downwardly 70 and forwardly to bring the cam portions into engagement with the free edge of the jaw or plate 4, whereby the latter may be moved downwardly toward the plate 1.

The plate 1 is provided with a pair of 75 spaced punch pins or posts 10 which are rigidly fixed thereto, while the jaw or plate 4 is formed with openings 11 in alignment with said pins and which are adapted to permit of the upward passage of the pins 80 when the jaw is forced down. Extending longitudinally between the pins 10 is a spring metal strip 12 centrally fastened to the plate 2, as by a rivet 13, said strip thence having its end portions extending upwardly 85 and outwardly at an angle toward the sides of the punch and terminating above the punch pins 10, said ends of the strip being provided with openings 14 of a size to permit of the free passage of the pins when the 90 jaw is operated.

It will be understood from the foregoing description that in the use of the device the edge of the sheet of paper to be punched is inserted into the space 5 between the strip 12 95 and the overlying portion of the jaw 4, and the said jaw is then forced down by means of the cam lever, whereby said jaw will be moved down over the punch pins and will cut out portions of the paper, the ends of 100 the spring strip being forced down to permit of the passage of the pins through the opening 7 in the jaw or plate 4. The openings being thus punched in the sheet of paper, the operating lever is moved backwardly, whereupon the jaw 5 will be automatically retracted by its spring action and the ends of the spring strip 12 will also move upward on the punch pins and force 105 the sheet of paper out of engagement with 110

said pins, and at the same time displace and discharge the punched out portions of the paper. By the use of a perforated spring strip for this purpose, an all metal punch is provided which is not only simple of construction but of maximum durability and may be made at a comparatively low cost.

I claim:—

1. A paper punch comprising a base plate, a pair of punch pins projecting from the base plate, a resilient punch plate movable toward and from the base plate, said punch plate having openings therein to receive said punch pins, a lever for adjusting the punch plate, and a ribbon spring having a flattened central portion secured to the base plate at a point equi-distantly between the punch pins, said spring having arms extending in opposite directions at an angle from said flattened portion toward the punch pins and terminating in flattened end portions lying parallel with the base plate, said flattened end portions being arranged to overhang

and apertured to slidably engage the punch pins.

2. A paper punch comprising a base plate, a pair of spaced punch pins projecting from the base plate, a resilient punch plate movable toward and from the base plate and having openings therein to receive said punch pins, a lever for adjusting the punch plate, and a ribbon spring secured to the base plate at a point between the punch pins, said spring having arms extending from its point of attachment toward the punch pins and bent upward at an angle so as to lie above the base plate and having its end portions apertured to slidably engage the punch pins.

In testimony whereof I affix my signature in presence of two witnesses.

JOHN McLUCKIE.

Witnesses:

N. H. COLEHOWER,
JESSE G. SCOTT.
